G. H. FORSYTH.
WINDOW CONSTRUCTION.
APPLICATION FILED AUG. 12, 1907.

1,063,346.

Patented June 3, 1913.

UNITED STATES PATENT OFFICE.

GEORGE H. FORSYTH, OF CHICAGO, ILLINOIS.

WINDOW CONSTRUCTION.

1,063,346.

Specification of Letters Patent.

Patented June 3, 1913.

Application filed August 12, 1907. Serial No. 388,180.

To all whom it may concern:

Be it known that I, GEORGE H. FORSYTH, a citizen of the United States, residing at Chicago, in the county of Cook and State of Illinois, have invented certain new and useful Improvements in Window Constructions, of which the following is a specification.

This invention relates in general to window constructions, and has reference more particularly to a construction employing, in combination with a suitable guide, one or more closures for the window opening; which closure or closures, within the purview of the invention, may consist of one or 15 a plurality of plates of glass, or of a glass plate in association with a shutter or curtain, whether of metal or other material, or of one or more shutters adapted to be employed as a closure and air guard to the 20 opening for any purpose or purposes.

In respect to the main novel features of the invention, these may be said to consist in part of a novel construction of closure employing one or more frameless plates 25 adapted to increase the extent of sight opening as compared with a regular window sash, in part of elastic or resilient means whereby one or more of the plates is made to engage the guide, and means whereby two 30 or more of the plates may be normally and elastically spaced and held apart.

My invention also comprises novel means providing for an automatic edgewise adjustment of the plates in their guides, as 35 likewise a novel construction of telescoping closure.

The invention will be readily understood when considered in connection with the accompanying drawings, which show approved mechanical forms of the several features of the invention, and in which,—

Figure 1 is a horizontal section on the line 1—1 of Fig. 2, showing a telescoping form of sash employing twin frameless plates in 45 both the upper and lower sections thereof. Fig. 2 is a vertical sectional view substantially on the line 2—2 of Fig. 1. Fig. 3 is a horizontal section through one margin of the plates and their guide, illustrating 50 means employed in association with the guide for automatically spacing the plates, maintaining a snug fit of the latter in the guide, and automatically adjusting the plates edgewise relatively to the guide. Fig. 55 4 is a view similar to Fig. 3, showing a construction wherein the spacing and automatic

adjusting means are carried by the margin of the plates. Fig. 5 is a view similar to Figs. 3 and 4, showing in cross-section upper and lower double plate sashes, with elastic 60 sheet metal devices for both spacing the plates and maintaining a snug sliding fit of the sash in the guides; said figure also showing a form of bent metal strip adapted to grip the margins of the plates under pressure, as likewise means for adjusting the plates edgewise. Fig. 6 is a detail of a compound bent sheet metal plate-holder such as shown in the lower half of Fig. 5. Fig. 7 is a fragmentary view of a plate such as may 70 be employed in my invention to form one or both of the closures, said plate having a novel form of margin strip requiring to be fastened to the plate only at its ends.

Referring first to Figs. 1 and 2, 10 designates a section of a jamb-post of a window frame, and 11 designates each of a pair of guide-strips secured thereto, and together constituting the guide for the sash or other closure of the window opening. The free 80 margins of these guide-strips are outwardly flared as shown at 11^a, and said guide-strips are adapted to receive the marginal portions of a pair of frameless plates 12 which, in the present instance, constitute the upper 85 section of a telescoping double plate closure. The margins of said plates have inwardly turned flaring or inclined portions 12^a adapted for sliding contact with the flaring margins 11^a of the guide-strips. Secured to 90 the jamb-post 10 below the guide-strips 11 are a similar pair of narrower guide-strips 13 having similar flaring margins 13^a, which guide-strips may conveniently constitute the side walls of a single channel-shaped strip 95 suitably secured to the jamb-post. The lower guide-strips 13 are engaged by a pair of lower frameless plates 14 having inwardly turned or inclined marginal portions 14^a slidingly engaging the outwardly flared 100 margins 13^a of the guide-strips. One or more springs 15 interposed between the margins of the plates 14 operate to maintain the latter in snug sliding engagement with its guides; and similarly, one or more 105 springs 16 likewise expand the plates 12 against their coöperating guide-strips 11. The lower margins of the upper plates 12 have inwardly turned projections 12^b, and the upper margins of the lower plates 14 110 have similar outwardly turned projections 14^b which projections form coöperating

stops to prevent separation of the upper and lower series of plates, while permitting free sliding or telescoping movement of the plates 14 within the plates 12.

5 Secured to one of the plates 14 is a suitable lift 17 which, where the plate is made of metal, may conveniently be formed by cutting and bending outwardly a tongue from the metal of the plate; the opening 17^a thereby formed being closed by a cover 18 secured to the other side of the plate over said opening. The lower margins of the plates 14 are adapted to abut against a sill member indicated at 19, and are separated as shown at 14^b to permit the escape of dust and dirt therebetween, or, said plates may be connected at their lower edges and provided with sufficient openings or apertures for the same purpose. In operation, the lower section 14 of the sash or other closure is raised 10 in its guides 13 until the lift 17 strikes the lower edge of the upper section 12, whereupon the latter section, with the lower section telescoped therein, is raised in its guides 11.

15 Figs. 3, 4 and 5 illustrate a variety of devices which may be employed for the purpose of securing a snug sliding fit of one or both of the plates with their respective guides, as likewise for effecting an automatic edgewise adjustment of the plate or plates in their guides; and it should be understood that these devices are applicable to any closure employing a plate or a pair of 20 separated or spaced plates, and, when used with a telescoping construction as shown in Figs. 1 and 2, may be applied to either or both of the upper or lower sections. Referring to Fig. 3, 14 may designate parallel 25 plates, the same having their marginal portions bent inwardly at an oblique angle to the plates, as shown at 14^c. The guide-strips 20 which are secured to the jamb-post 10 are bent inwardly at their free margins parallel 30 with the strips, as shown at 20^a and constitute the immediate guiding and contacting parts engaging the outer surfaces of the plates 14. Within the hollow guide formed by and 35 between the guide-strips 20 is located a W-shaped adjusting strip 21, the outer parallel sides of which are guided between the strips 20 and their inwardly turned margins 20^a; while the intermediate V-shaped portion of 40 said adjusting strip engages the oblique margins 14^c of the plates. The strip 21 is normally pressed outwardly or into engagement with the margins of the plates 14 by one or more springs 22 interposed between the jamb-post 10 and a triangular filling strip 45 23 lying behind the apex or V-shaped central part of the adjusting strip. It will be observed that by reason of this construction the adjusting strip not only maintains a snug marginal fit with the plates 14, but also 50 tends to spread the latter into snug sliding

engagement with the inwardly turned margins 20^a of the guides 20.

55 In the form of the invention illustrated in Fig. 4, the means for spreading or distending the plates and effecting a snug sliding fit of the sash in its guide are carried by the plates 14. In this figure 24 designates a substantially M-shaped guide-strip that may be conveniently bent to shape from a strip of sheet metal, and that is secured at its opposite edges to the jamb-post 10. The outer surface of this guide is herein shown as covered by a sheath or coating of non-corrosive metal or other material indicated at 25. The adjacent margins of the plates 14 are engaged by a sheet metal stile member that may be formed from a strip of sheet metal bent longitudinally to provide a central or intermediate bow spring 26, on either side of which is a channel-shaped portion 27 adapted to receive and grip under tension the margins of the plates; while outside of said channel-shaped portions are formed side walls 28, the marginal portions of which are bent inwardly obliquely, as shown at 28^a, 60 and slidably engage the inclined walls of the central or intermediate V-shaped portion of the guide. In this construction the bow spring 26 normally operates to spread or distend the plates 14, holding them spaced or 65 separated at a proper interval; while the side walls 28, through their transverse resiliency, engage the inclined walls of the guide under pressure, thus producing a snug sliding fit with the guide. Furthermore, the 70 inclination of the contacting parts of the stile and guide, under the transverse resiliency of the former, permits automatic edgewise adjustment of the plates between the opposite vertical guides in which they 75 are mounted.

75 In Fig. 5 I have shown in part a pair of sash members, one of which may be assumed to represent an upper sash member and the other an offset lower sash member engaged 80 with their respective guides on the jamb-post; and in connection therewith I have shown modified forms of bent sheet metal finishing strips or stile members for the plates which also embody therein means for 85 separating or spacing the plates. In this view, 29 designates a U-shaped guide secured to the jamb-post 10, which guide may be assumed to represent the guide of the upper sash, the two plates of which are designated 90 at 14^d; while 30 designates a W-shaped guide likewise secured to the jamb-post 10 and engaged by the marginal or finishing strips or stiles of a lower sash member, the two plates of which are designated by 14^e and 14^f. Between the guides 29 and 30 is a parting strip 31. The guides in both instances are herein shown as provided with a coating or sheathing 25 of non-corrosive material, as in Fig. 4. The margins of the 95 100 105 110 115 120 125 130

plates 14^e are overlapped on both sides by a pair of bent metal finishing strips 32 which may conveniently be secured thereto by punching or offsetting parts of the metal thereof shown at 32^a into holes 33 formed through the plates.

34 represents a bow spring interposed between the plates with its margins conveniently connected to the inwardly offset margins of the finishing strips 32 as by rivets 35.

The plates 14^e and 14^f are equipped with a one-piece or integral marginal member or stile that, like the construction shown in Fig. 4, embodies in itself the means for gripping the plates, the guide-engaging means, and the means for separating or spacing the plates. This member, which is shown in isolated detail in Fig. 6, comprises essentially a pair of W-shaped members 36, the adjacent limbs of which are connected by an integral reentrant and transversely elastic loop 37. The reentrant central portions 36^a of the members 36 are made somewhat contracted at their open ends, as shown in Fig. 6, so as to grip the plates 14^e and 14^f under considerable pressure, and are secured to the plates preferably by inwardly punched portions entering the apertures in the plate, as described in connection with the members 32, while the outer side portions of the members 36 are normally outwardly divergent so as to be compressed between the walls of the guide 30 when inserted therein and produce a snug sliding fit therewith. The two limbs of the reentrant loop 37 similarly engage under transverse pressure the intermediate parting strip 30^a of the double guide 30. In order to effect automatic edgewise adjustment of the plates 14^e and 14^f, I employ a pair of hollow sheet metal strips 38 that lie between and are secured to the outer side members of the W-shaped portions of the finishing strip and through pin-and-slot connections indicated at 39 permitting the horizontal play of the strips 38. Said strips are normally pressed outwardly into engagement with the transverse walls of the guide through compression springs 40 interposed between the inner edge of the adjusting strips and the transverse members of the reentrant portions 36^a.

In Fig. 7 I have shown what I believe to be a novel form of finishing strip, such as

32, designed to maintain a snug fit of such strip on the edge of the plate throughout its entire length, with only a single fastening necessary at either end. This is secured by bowing the strip between its upper and lower ends so as to cause the transverse member of the strip to present a slightly convex longitudinal surface to the edge of the plate, and then forcing the outwardly bent ends of the strip inwardly upon the edge of the plate and securing the same as by pins or rivets at each end to the plate. 65

I claim:

1. A sheet-metal window sash bent to provide a pair of parallel grooves having resilient walls for the accommodation of a pair of plates, said sash having a portion between the plates forming parts of said grooves and acting to resiliently maintain the plates in proper spaced relation, substantially as described.

2. A sheet metal window sash having walls bent to provide a pair of parallel grooves for the accommodation of a pair of plates, said sash having a portion between the plates forming part of said grooves and acting to resiliently maintain the plates in proper spaced relation, the sash when disengaged from its guide groove being wider than said groove, and thereby maintaining spring engagement with the sides of said groove when engaged with the same, substantially as described.

3. A sheet metal window sash having walls bent to provide a pair of grooves and having flexible spring engagement with a pair of plates, said sash having a portion between the plates which forms part of the walls of said grooves and acts to maintain the plates in proper spaced relation, substantially as described.

4. A metal window sash having walls bent to provide parallel grooves for the accommodation of a pair of plates and resilient means disposed between said grooves for maintaining said sash walls in lateral engagement with the walls of the sash guide, substantially as described.

GEORGE H. FORSYTH.

Witnesses:

SAMUEL N. POND,
FREDERICK C. GOODWIN.
